UNITED STATES PATENT OFFICE.

SVEN JULIUS STRID, OF CHICAGO, ILLINOIS, ASSIGNOR TO FRED MATHEWS, OF CHICAGO, ILLINOIS.

MOUNTING FOR BRAKE GEARS.

Application filed August 5, 1925. Serial No. 48,427.

To all whom it may concern:

Be it known that I, SVEN JULIUS STRID, a citizen of the United States, and a resident of Chicago, Cook County, Illinois, have invented certain new and useful Improvements in a Mounting for Brake Gears, of which the following is a full, clear, and exact description, such as will enable others to make and use the same.

My present invention relates to a structure for mounting a gearing for railway-car brakes and has more specific reference to a device that may be readily attached to the end-sill of the car and is so constructed that the mounting will be securely braced against the pull of the brake take up rod or chain. The essential feature of the present structure comprise a gusset or bracket secured to and projecting in an outward direction away from the end-sill and coacting therewith in a casting that comprises the upper member of the journaling structure which is a wide plate of almost square dimensions that is connected to the flange of the sill and has an upstanding wall that is secured to the gusset, thus rigidly connecting the structure to the sill.

I prefer to carry out my invention and accomplish its divers objects in substantially the manner hereinafter fully described and as more particularly pointed out in the claims, reference being here made to the accompanying drawings that form a part of this specification.

In the drawings:—

Fig. 1 is a transverse section of the car end-sill showing the application of my improved mounting thereto, said mounting being in side elevation.

Fig. 2 is a top plan of the structure shown in Fig. 1.

Fig. 3 is a front elevation of the mounting secured to the end-sill.

The drawings which are in a sense diagrammatical, illustrate a typical or preferred embodiment of my invention, and in these drawings I have employed similar reference characters to designate like parts wherever the same appear throughout the several views.

The end-sill in the present structure comprises a channel beam the web 5 of which is vertically disposed and the lateral top and bottom flanges 6, 6, which project in an outward direction away from the web as shown

in Fig. 1 of the drawings, and the brake mast 7 is positioned outside the wall or body 8 of the car. In order to accommodate the brake-gear in such an arrangement at the same time and brace the mounting structure against the longitudinal pull of the take-up chain or rod, I secure a triangular gusset 8 to the web of the sill intermediate the flanges of the latter, the gusset being provided with a lateral flange 9 along its vertical edge that fits against the outer surface of the sill and is riveted or bolted thereto.

The bottom member of the housing consists of a horizontal plate 10 having upstanding flanges 11 at its transverse end edges and mediate the longitudinal edge of this plate there is downwardly and inwardly projecting arm 12 that extends inwardly back of the plane of the end-sill. Bearings are provided in the plate and the arm for rotatably mounting the gears and winding drum.

The top member of the housing is preferably an integral casting and consists of a horizontally disposed plate 13 that has a vertically disposed wall 14 arising from the upper surface of the same and extending in a plane longitudinally of the car or transverse to the web of the sill and it is parallel with the gusset 8 to which latter it is secured by rivets or otherwise. The wall 14 is braced by inclined ribs 15 extending upwardly from the top of the plate 13. As will be noted from Fig. 2 the plate 13 is nearly square in shape and an edge portion thereof extends under and is riveted to the lower flange of the sill and there is an embodiment 16 that projects inwardly beyond the plane of the sill to provide one of the upper bearings for the gear elements. Plate 13 has depending flanges 17 at its ends that preferably overlap and are bolted or riveted to the upstanding flanges 11 of the bottom plate so that the two parts of the housing may be secured rigidly in assembly and with the gear elements in position provides a unitary structure. Thus it will be seen that the housing together with the gear members may be readily attached to the end-sill and provision is made to receive the brake mast outside the vertical plane of and spaced from the body or end wall of the car.

What I claim is:—

1. A brake gear mounting structure comprising the combination with the end-sill of

a railway car, of a gusset secured to and projecting downwardly from said sill; a top casting consisting of a plate of rectangular shape disposed beneath and secured to the 5 bottom flange of the sill; a vertical wall integral with the upper surface of the plate parallel with and secured to said gusset, a bottom casting consisting of a plate secured in spaced relation to said top plate and an arm 10 extending from the bottom plate inwardly with respect to the car, and gears journaled between said top and bottom castings.

2. A brake gear mounting structure comprising the combination with a car end-sill 15 of channel section, of a gusset secured to the web of the sill and projecting laterally outwardly therefrom, a plate secured to the under surface of the bottom flange of the sill and extending outwardly below the plane of 20 said flange; a wall arising from said plate beyond the sill flange and secured to said gusset, and a plate spaced from the first-named plate and connected thereto, whereby the gear elements are rotatably mounted between said plates below said sill and beyond 25 the vertical plane thereof.

3. The combination with a car end-sill of channel section with its flanges disposed out-

wardly with respect to the car, of a plate secured underneath the bottom flange of the 30 sill and projecting outwardly therefrom, a vertical wall arising from the plate immediately outside the edge of the bottom flange and projecting above the same, a gusset connecting said wall to the sill independently of 35 the flange, and a member secured to said plate and spaced below the same, said plate and member provided with bearings whereby to rotatably mount the gear elements between the plate and member and position the 40 brake mast in a vertical plane outside and beyond the sill and body of the car.

4. In means for mounting a brake gearing on a car end-sill, a gusset secured to and projecting outwardly from the sill, a plate secured to the lower portion of the sill and extending outwardly therefrom below said gusset, and an upstanding element on the upper surface of said gusset, and an upstanding element on the upper surface of said plate 45 50 that is rigidly connected to said gusset forwardly of the sill.

Signed at Chicago, Cook County, Illinois, this 7th of July, 1925.

SVEN JULIUS STRID.
